(57) **CLAIM**

The ornamental design for an edge protector, as shown and described.

DESCRIPTION

FIG. 1 is a perspective view of the interior of an edge protector showing my new design;

FIG. 2 is a perspective view of the exterior thereof;

FIG. 3 is an elevational view of a side of the interior thereof; FIG. 4 is an elevational view of the side adjacent of the interior thereof;

FIG. 5 is an elevational view of a side of the exterior thereof; FIG. 6 is an elevational view of the side adjacent of the exterior thereof; and,

FIG. 7 is an enlarged end elevational view thereof, the end opposite being a mirror image of that shown.
